(57) **CLAIM**

The ornamental design for a drink holder, as shown and described.

DESCRIPTION

FIG. 1 is a perspective view of the drink holder.

FIG. 2 is a front elevation view thereof.

FIG. 3 is a rear elevation view thereof.

FIG. 4 is a top side view thereof.

FIG. 5 is a bottom side view thereof; and,

FIG. 6 is a first side view thereof, the second side view opposite the first side view being a mirror image thereof. The rim of the drink holder and opening in the bottom surface shown in broken lines form no part of the claimed design.
